UNITED STATES PATENT OFFICE.

JOHN K. STEWART, OF CHICAGO, ILLINOIS, ASSIGNEE TO STEWART-FAIRWEATHER SEPARATOR CORPORATION, OF CHICAGO, ILLINOIS, A CORPORATION OF VIRGINIA.

DRIVE-GEARING FOR SHAFT-SPEED INDICATORS.

1,152,569.

Specification of Letters Patent. Patented Sept. 7, 1915.

Application filed December 13, 1912. Serial No. 804,454.

To all whom it may concern:

Be it known that I, JOHN K. STEWART, a citizen of the United States, residing at Chicago, in the county of Cook and State of Illinois, have invented certain new and useful Improvements in Drive-Gearing for Shaft-Speed Indicators, of which the following is a specification, reference being had to the accompanying drawings, forming a part thereof.

The purpose of this invention is to provide a form of gear train peculiarly adapted for operatively connecting a shaft-speed-indicating instrument with the driving shaft of a cream separator of a particular type; but it will be understood that the invention is applicable to many other situations of an analogous character.

The features of novelty are hereinafter described and illustrated in the drawings, being particularly designated by the claims.

In the drawings: Figure 1 is a fragmental plan view indicating certain outlines of the cream separator and showing the speed indicator attached thereto in operative position. Fig. 2 is a vertical section, taken as indicated at line 2—2 on Fig. 1, and showing the detail construction of the drive gear which is the subject of this invention. Fig. 3 is a side elevation of the gear casing, being taken as a section at the line 3—3 on Fig. 2. Fig. 4 is a detail section taken as indicated at the line 4—4 on Fig. 2. Fig. 5 is a small side elevation of the speed indicator showing the drive shaft in section, and with a part broken away to show the gearing.

In Fig. 1, A designates the outline of the bowl of the machine in which the separation of the milk and cream takes place, while the rotary element contained in such bowl is driven through a gear train at B, and a drive shaft journaled in the bearing, C, extends across the machine at the rear of the bowl, A. This shaft is designed to be operated by a crank, D, disengagably connected through a ratchet clutch comprising a member, D¹, formed on the hub of the crank, D, and a co-operating member, E¹, fixed on the driving shaft, E, of the separator.

The speed-indicating instrument which is to be used for indicating the rotary speed of the shaft, E, is of a design illustrated in outline in Fig. 5, comprising a speed indi-

cator housed in a cylindrical casing, X, having a circular extension, X¹, in which there is journaled a spiral gear, Y, meshing with a spiral gear, Z¹, on the shaft, Z, of the speed indicator. This type of instrument is ordinarily applied to cream separators and like machines by securing its gear, Y, directly to the crank shaft of the machine, the casing, X¹, being journaled upon said shaft and stopped against rotation by any convenient connection to the main frame of the separator. With the present type of separator, however, the length of drive shaft which is exposed between the journal bearing, C, and the crank hub, D¹, is insufficient to accommodate the casing, X¹. It is therefore necessary to provide a "thin model" gear train for transmitting the motion of the drive shaft, E, to the speed-indicating instrument. With this purpose in view, the clutch member which is regularly fixed to the shaft, E, is replaced by the member, E¹, shown in the drawings, which has in addition to the clutch teeth, E¹, a set of spur gear teeth, H¹, formed on its periphery and designed to actuate a similar gear, F, through an idler pinion, G. These three gears are housed in a casing consisting of a casting, H, and a cover plate, H¹, said casing serving to support the speed indicator casing through a connection therewith in the form of a bushing, J, formed as a drive fit in the casing, X¹, and secured by a set screw, K, in a boss, H², of the casing, H. This form of attachment permits angular adjustment of the speed indicator casing so as to bring its scale window, K¹, into the plane at which it may be most easily read by the operator of the machine. A short shaft, L, journaled in the bushing, J, carries the gear, F, on one end secured thereto by a nut, F¹, and is rigidly fixed in the spiral gear, Y, so as to transmit motion from the drive train to the speed indicator. The idler pinion, G, is journaled on a stud fixed in a boss, H², at the casting, H, but the gear, E¹, on the clutch member, E¹, is not definitely located in the casing, X¹, except by the adjustment of said casing relatively to the driving shaft, E, of the cream separator.

Such adjustment is secured by means of three set screws, H³, carried in an annular boss, H⁴, in position to bear against the cylindrical journal bearing, C, of the shaft, E, so that by manipulation of these set screws, 110

H⁴, the casing, H, may be so positioned with relation to the shaft, E, as to secure proper meshing of the gear, E³, with the idler, G; and incidentally, such adjustment 5 serves to secure upon the cream separator the entire train together with the speed indicator itself. By means of this gear train, therefore, it becomes possible to use a standard type of speed indicator without re-designing its casing to fit in the close quarters afforded by the design of the cream separator, and incidentally the speed indicator is more conveniently positioned and is rendered adjustable to any desired angle to 10 facilitate the observation of its reading.

I claim:—

1. The combination of a rotary shaft, a cylindrical journal bearing therefor, and means for connecting thereto a mechanism 20 to be actuated thereby comprising a gear train, a housing for said gear train having an annular flange dimensioned to encircle the cylindrical journal bearing, and adjustable means carried by the flange adapted to 25 engage the journal bearing for securing the housing thereto.
2. In combination with a rotary shaft, a removable drive crank having a hub formed with clutch teeth, means for actuating a 30 mechanism by said shaft, comprising a sleeve fixed on the shaft, circumferentially provided with gear teeth, a gear train meshing therewith for communicating motion to said mechanism, said sleeve being also formed with clutch teeth adapted for engagement with those of the crank hub.
3. In combination with a rotary shaft, a 35 journal bearing from which it projects at one end, and a driving crank on said end of

the shaft, means for actuating from said shaft a mechanism whose casing is wider than the distance between said journal bearing and said crank, comprising a spur gear secured to the shaft between said journal bearing and said crank, a housing for said gear mounted on the journal bearing and extending transversely therefrom, a gear train in said housing terminating in a shaft parallel to the first-mentioned shaft, and means for supporting said mechanism on the extending portion of the housing in position to engage said final shaft of the train.

4. In combination with a rotary shaft, a journal bearing from which it projects at one end, and a driving crank on said end of 55 the shaft, means for actuating from said shaft a mechanism whose casing is wider than the distance between said journal bearing and said crank, comprising a spur gear secured to the shaft between said journal 60 bearing and said crank, a housing for said gear mounted on the journal bearing and extending transversely therefrom, a gear train in said housing terminating in a shaft parallel to the first-mentioned shaft, and a 65 bushing for said final shaft of the gear train projecting from the extending portion of said housing for supporting said mechanism, the casing of said mechanism having an aperture to fit tightly over said bushing, 70 and means for securing it thereto.

In testimony whereof witness my hand at Chicago, Illinois, this 10th day of December, 1913.

JOHN K. STEWART.
